Sheffield & Betts

UNITED STATES PATENT OFFICE.

HERMAN C. MAISE, OF SPRINGFIELD, MASSACHUSETTS, ASSIGNOR, BY MESNE ASSIGNMENTS, TO EDWARD G. BUDD MANUFACTURING COMPANY, A CORPORATION OF PENNSYLVANIA.

DOOR BUFFER.

Application filed June 21, 1916. Serial No. 104,899.

To all whom it may concern:

Be it known that I, HERMAN C. MAISE, a citizen of the United States, and a resident of Springfield, in the county of Hampden 5 and State of Massachusetts, have invented new and useful Improvements in Door Buffers, of which the following is a description.

My invention relates to vehicle doors and particularly to means for preventing the vibration thereof when the vehicle is in motion.

It has heretofore been proposed to prevent the vibration of vehicle doors by interposing a pad of resilient material or a spring between the door jamb and the edge of the door. In this way the horizontal vibration of the door has been largely eliminated but little reduction has been made in the amount of vertical vibration which is caused by the 20 "giving" of the vehicle body.

An object of my present invention is to provide means which will effectually prevent both horizontal and vertical vibration of the door, without in any way interfering with 25 its operation.

Another object of my invention is to provide simple and efficient means for retaining a resilient pad or buffer in position.

Other objects of my invention will appear 30 more fully hereinafter.

Referring to the drawing, Fig. 1 is an elevation of the door casing and jamb showing in section a small portion of the edge of the door with my improved means attached thereto, said section being taken on the line 1-1 of Fig. 2.

Fig. 2 is a fragmentary sectional view taken on line 2-2 of Fig. 1.

Fig. 3 is a detail showing a portion of the 40 door jamb; and

Fig. 4 is a perspective view of the resilient pad and its attaching means.

In the drawing the plates 10, 11, constitute 45 the door jamb. The plate 11 as shown in Figs. 2 and 3 is provided at its outer edge with a depression or recess 13 extending inwardly. As herein shown, this recess is semi-circular in form, and its curved edge is provided with a marginal flange 14.

The device 15 shown in Fig. 4 for attachment to the edge of the door comprises a substantially U-shaped metallic casing 16 within which is placed the resilient pad 17.

The outer plate 18 of the casing is preferably of less length than the pad 17, and the inner plate 19 is preferably of greater length.

The outer plate 18 is provided with an aperture 20, and the inner plate 19 is provided with an aperture 21 located beyond the extremity of the pad 17 and an aperture 22 in alignment with the aperture 20 of plate 18. The means for attaching the device 15 to the edge of the door D comprise preferably the screws 23, 24, the former of which passes through the aperture 21 in plate 19, and the latter of which passes through the apertures 20 and 22 in the plates 18 and 19 respectively, and through the resilient pad 17. The latter screw, therefore, serves not only to secure the device to the door, but also to retain the pad 17 within its casing.

The pad 17 is of substantially the same configuration as the recess or depression 13 and therefore when the door is closed this pad contacts with the curved marginal edge or flange of the recess 13. This contact between the pad and the marginal edge of the recess occurs at the bottom and top as well as at the inner edge of the recess, and it is because of this fact that my improved device is so effective in preventing not only horizontal vibration of the door, but also vertical vibration thereof.

While my invention is not limited to the use of a semi-circular recess and a semi-circular pad, I find this particular configuration to be of particular advantage since, as will readily be understood, it results in a self-centering action between the pad and recess. This action may be facilitated, if desired, by mounting the pad 17 loosely in its casing, so that it is free to rotate about the screw 24 as a pivot.

It is obvious from the above that my improved device though of simple and inexpensive construction effects the desired results in a most effective and reliable manner.

What I claim is:

1. A device of the character described comprising a substantially U-shaped metallic casing having inner and outer walls and an integral base connecting said walls, a resilient pad positioned between the inner and outer walls and seating on said base, the outer wall being of less length than said pad

and the pad presenting a semi-circular portion projecting beyond said outer wall, and means for retaining said pad in the casing.

2. Means for preventing the vibration of a vehicle door comprising a door jamb provided with a semi-circular recess extending inwardly from the outer edge thereof, in combination with a device to be attached to the co-operating edge of the door and comprising a substantially U-shaped metallic casing, having inner and outer walls and an integral base connecting said walls, a resilient pad interposed between the inner and outer walls of said casing and seating against the base connecting said walls, the outer wall

being of less length than the pad, said pad presenting a semicircular portion which projects beyond the edge of said outer wall, means for securing the device to the edge of the door, and means for retaining the pad 20 within the casing, the semicircular projecting portion of said pad being adapted to be received in the semicircular recess in the door jamb and to contact with the inner, top and bottom marginal edges of said semicircular recess when the door is closed, to prevent vertical as well as horizontal vibration of the door. 25

HERMAN C. MAISE.
